UNITED STATES PATENT OFFICE.

ALBIN LESSING, OF JERSEY CITY, NEW JERSEY.

PHOTOGRAPHIC-PRINTING APPARATUS.

1,413,746.

Specification of Letters Patent. Patented Apr. 25, 1922.

Application filed June 19, 1920. Serial No. 390,082.

To all whom it may concern:

Be it known that I, ALBIN LESSING, a citizen of Germany, and resident of Jersey City, county of Hudson, and State of New Jersey, have invented certain new and useful Improvements in Photographic-Printing Apparatus, of which the following is a specification.

My invention relates to apparatus for printing photographs and has for its object to provide an apparatus of novel construction adapted for either plate or film printing and which, when used for the latter purpose, does not require the film to be cut into sections corresponding to the individual pictures contained therein, prior to the printing thereof. Other more specific objects of my invention will appear from the description hereinafter and the features of novelty will be pointed out in the appended claims.

In the accompanying drawings which show an embodiment of my invention, without defining its limits, Fig. 1 is a sectional elevation of the apparatus; Fig. 2 is a front elevation partly broken away; Fig. 3 is a detail section on an enlarged scale, and Fig. 4 is a fragmentary side view.

As shown in the drawing the apparatus comprises a receptacle or body 10 of suitable material and dimensions and provided with a movable cover 11 whereby access to the interior of said receptacle may be had. A casing 12 extends upwardly from the body 10 and communicates with the interior thereof, said casing having a light pervious panel 13 of glass or other translucent or transparent material set into its front wall as shown in Fig. 2 and preferably further having a movable cover 14 located at a point to provide for convenient and ready access to the interior of said casing. Provisions may also be made for the accommodation and positioning of suitable masks 15 in front of the light pervious panel 13 to variably define the active area thereof.

Studs 16 and members 17 are mounted in the casing at its upper end, the members, at least, being rotatable, and are arranged to receive the opposite ends of reels 18 and 19, the connections preferably being such as to enable the ready insertion and removal of said reels when desired.

In the preferred construction the flanges 20 and 21 of the reels 18 and 19 respectively are arranged so as to be adjustable toward

and away from each other and are fixed in their adjusted positions by means to set screws 22 or their equivalents. Gears 23 are fixed upon the rotatable members 17 and are operatively connected by means of a pinion 24 located upon a shaft 25 journaled in said casing and extending exteriorly thereof, the projecting end of said shaft being provided with a key 26 or other device whereby rotation thereof may be manually accomplished.

A brush 27 mounted upon a back 28 is contained within the casing 12 in registry with the panel 13 and is pressed toward the latter by means of a spring 29 preferably secured to the back 28 and engaging the rear wall of said casing 12 as shown in Fig. 1.

In the operative condition of the apparatus the film 30 which is to be printed passes from the receptacle 10 in which it is contained over a suitable guiding device 31 and in back of the light pervious panel 13 and to the reel 18 to which its end is detachably connected in any convenient manner. A roll of sensitized paper 32 on which the photographs are to be printed is rotatably mounted in the receptacle 10 and passes therefrom over the guiding device 31 between the film 30 and the brush 27 to the reel 19 to which its end is detachably secured in any well known way. By rotatably actuating the key 26 the pinion 24 and consequently the gears 23, are rotated to wind the film upon the reel 18 and concurrently to wind the sensitized paper 32 upon the reel 19 and thus to bring the first picture upon the film 30 and an active section of the sensitized paper 32 into registry with the light pervious panel 13. After the first picture has been exposed the desired period of time to complete the printing, the key 26 is again actuated to bring the second picture on the film 30 and a new active section of the paper 32 into registry with said panel 13 to print said second picture, this operation being repeated successively until all the pictures upon a given film have been exposed and printed.

During the shifting of the film and sensitized paper, the brush 27 maintains the same under a tension whereby both film and paper are prevented from wrinkling, while during exposure when film and paper are stationary, said brush serves to maintain the paper in firm and even contact with the film and to press both film and paper evenly and

uniformly against the light pervious panel 13. The action of the brush is such that the film and paper will be properly held in position down to and including the last picture, so that all of the pictures on a given film may be exposed without difficulty. After one film has been completely exposed and printed both reels 18 and 19 upon which the film and paper have respectively been 10 wound, may be bodily removed from the apparatus or said paper and film may be unwound from said reels as desired. The removal of the printed paper, of course, takes place in a dark room and may be followed 15 either immediately or subsequently by such steps as are required to complete the production of the pictures. It will of course be understood that suitable provision is made to prevent light from reaching the interior 20 of the body 10 where the roll of paper 32 is located and also from reaching that part of the casing 12 in which the reel is positioned.

Prior to the actual printing operation, a 25 suitable mask 15 may be placed in front of the panel 13 to define the area required for the particular film being exposed and the flanges 20 and 21 may be adjusted to correspond to the width of said film and of the 30 sensitized paper respectively. By selecting a mask suitable for the purpose or by providing a specially constructed panel 13, the apparatus may be readily adapted for efficiently exposing moving picture films. The 35 apparatus may also be utilized as an ordinary printing frame to print individual pictures and for plate printing by simply placing the individual film or plate with the required sheet of sensitized paper between the 40 panel 13 and brush 27. In order to facilitate the printing of such individual films or plates it is desirable to have the panel 13 in an inclined position, this result being attained either by tilting the entire apparatus 45 or by making provision for tilting the casing 12 relatively to the body 10.

The apparatus is simple in construction and efficient in operation and does away with the necessity for cutting a film into

sections corresponding to the individual pictures thereon, thus not only retaining the film in its original complete condition, but also increasing the output of finished pictures.

Various changes in the specific form 55 shown and described may be made within the scope of the claims without departing from the spirit of my invention.

I claim:

1. A photographic printing apparatus 60 comprising a body arranged to contain a photographic film and a supply of sensitized paper, an upright casing divided into an upper and a lower interior chamber and extending upwardly from said body and 65 communicating therewith, an upright light pervious panel in one wall of said casing in registry with the lower chamber thereof, a pair of reels journaled in the upper chamber of said casing and arranged to independently receive said film and paper respectively, gears operatively connected with said reels, a pinion in mesh with said gears, a key for rotating said pinion and gears whereby said reels are actuated to concurrently adjust said film and paper in registry with said panel, a brush located in the lower chamber of said casing and having its bristles in direct surface contact with said paper and a spring whereby said brush is resiliently pressed against said paper to press it and said film into surface contact with each other and with said panel. 75

2. In a photographic printing apparatus, the combination of a light pervious panel, a 80 container for a photographic film and a supply of sensitized paper, means for separately feeding said film and paper to progressively and concurrently adjust them in registry with said panel, a brush having its bristles in direct contact with said paper and a 85 spring whereby said brush is resiliently pressed against said paper to press it and said film into surface contact with each other and with said panel. 90

In testimony whereof I have hereunto set my hand.

ALBIN LESSING.
